UNITED STATES PATENT OFFICE

150,999

DESIGN FOR A MOTOR VEHICLE

Gregory Miller and Monte Sinderman,
Los Angeles, Calif.

Application October 14, 1946, Serial No. 133,944

Term of patent 3½ years

(Cl. D14—3)

To all whom it may concern:

Be it known that we, Gregory Miller and Monte Sinderman, citizens of the United States, residing at Los Angeles, in the county of Los Angeles and State of California, have invented a new, original, and ornamental Design for Motor Vehicle, of which the following is a specification, reference being had to the accompanying drawing, forming a part thereof, and in which:

Fig. 1 is a side elevational view of the motor vehicle, showing our new design.

Fig. 2 is a top plan view of the motor vehicle shown in Fig. 1.

Fig. 3 is a front end elevational view of the motor vehicle.

Both sides of the motor vehicle are similar in design.

We claim:

The ornamental design for a motor vehicle, as shown and described.

GREGORY MILLER.
MONTE SINDERMAN.
